DESIGN FOR A MACHINE FOR SURFACING
AND POLISHING FLOORS

Richard F. Kneisley and Robert E. Wolfe, Toledo,
Ohio, assignors to The American Floor Surfacing
Machine Company, Toledo, Ohio, a corporation
of Ohio

Application May 6, 1938, Serial No. 77,046

Term of patent 14 years

To all whom it may concern:

Be it known that we, Richard F. Kneisley and Robert E. Wolfe, citizens of the United States and residents of Toledo, in the county of Lucas and State of Ohio, have invented a new, original, and ornamental Design for a Machine for Surfacing and Polishing Floors, of which the following is a specification, reference being had to the accompanying drawing forming a part thereof.

Fig. 1 is a front perspective view of a machine for surfacing and polishing floors showing our new design;

Fig. 2 is a top plan view thereof;

Fig. 3 is a perspective view showing the opposite side from Fig. 1, and

Fig. 4 is a rear end view of the machine.

In Figs. 1, 2 and 3 the handle and cord portions are shown broken away for convenience of illustration.

The dominant feature of our design resides in the shaded solid line portion of the body casting.

We claim:

The ornamental design for a machine for surfacing and polishing floors, substantially as shown and described.

RICHARD F. KNEISLEY.
ROBERT E. WOLFE.
